CONTAINER FOR EXPLOSIVES

**Carey O. Rison, Oklahoma City, Okla., assignor
of one-half to Indian Territory Illuminating
Oil Company, Bartlesville, Okla., a corporation
of New Jersey**

Application November 15, 1933, Serial No. 698,100

6 Claims. (Cl. 102—4)

My invention relates to containers for high explosives and the method of making the same, and particularly those of that character employed in lowering a charge of liquid nitro-glycerine, or other explosive, into a well to a predetermined depth for detonation as when "shooting" a well, or for other purposes incidental to oil field practice.

Due to the instability of nitro-glycerine used in the oil and gas industry, many premature explosions are directly caused by the nature and character of the container for the reason that containers as heretofore employed do not protect the explosive from effects causing its premature decomposition and/or explosion. For example, many explosions are caused by transfer of heat through the walls of the container incidental to friction or abrasion thereof with the walls of the well while the charge is being lowered, resulting in expansion of the liquid and in many instances the expansion occurs to such an extent as to cause overflow of the container.

Other explosions are caused by conduction of earth electricity through the walls of the container, by static electricity generated incidental to the lowering operation, and by leakage of the container through puncture and failure of the joints or seams.

Attempts have been made to overcome some of the above defects by constructing the container from non-metallic material, such as fibre impregnated paper, wood pulp, or of plastic substances, such as asphalt, or asphalt-gilsonite, and the like.

These containers, however, have not proved satisfactory, owing to the fact that acidity is residually present in their composition, or acidity is later created by chemical reaction in the materials themselves. The presence of acidity is a most likely cause for premature explosion because acidity tends to the instability of the explosive and in many instances sets up a chemical reaction producing its decomposition. Such containers are also subject to effects of solubility, heat and frangibility under high hydrostatic pressure, all of which tend to cause of premature explosions.

In many instances, the containers, even when they are properly placed in a well do not completely shatter under the force of the explosion with the result that large pieces driven from the top of the well are likely to strike sparks that may ignite the well flow, or they may cause serious injury to persons in the vicinity of the well.

These large pieces also, in many instances, pro-

duce a bridging effect in the well that requires considerable expense on the part of the producer in drilling out or around the bridge.

Containers of a plastic nature, such as those constructed of asphalt, or asphalt-gilsonite, often cause irreparable damage to the well for the reason that the heat and force of the explosion drives the softened material deeply into the sand, thereby closing the pores and flow channels through which oil enters the well.

The principal objects of the present invention are, therefore, to provide a container having dielectric properties, capable of resisting static or other electric currents and magnetic conditions in the well, to provide a shell body that is dense and hard so that it will not absorb the explosive or well fluids, to provide a container that is a relatively poor conductor of heat either through friction or high well temperatures, to provide a container that resists abrasion and punctures, to provide a container construction that readily withstands hydrostatic pressures in the well, but which is of extremely light weight so that it is readily disrupted into very small fragments under force of the explosion, and to provide a container that is entirely free from acidity or material that will chemically react with the explosive.

In accomplishing these and other objects of the invention, I have provided improved details of structure, the preferred forms of which are illustrated in the accompanying drawing, wherein:

Fig. 1 is a vertical sectional view through a well hole illustrating a nitro-glycerin containing shell constructed in accordance with my invention and shown as being lowered into position for "shooting" a well.

Fig. 2 is a perspective sectional view of the container.

Fig. 3 is a cross sectional view through the container on the line 3—3, Fig. 2.

Fig. 4 is a detail sectional view through the funnel member on the line 4—4, Fig. 2, particularly illustrating the vent openings for relieving the container of air as it is being filled with nitro-glycerin.

Fig. 5 is a vertical section through a modified form of shell completely closed at both ends and adapted for containing an explosive and a timed or automatic detonating, exploding, or igniting device.

Fig. 6 is a vertical section through a container equipped with a modified form of funnel member, and showing the tubular sections secured together by a threaded insert.

Fig. 7 is a similar view through a still further

modified form, wherein the tubular sections of the container are secured together by a sleeve insert.

Referring more in detail to the drawing:

1 designates a container which includes an elongated cylindrical body of suitable diameter to pass through the well casing 2 and of sufficient length to contain the required amount of explosive depending upon the nature and purpose of the explosive effect desired. The cylindrical wall 3 of the container may be constructed of one or more tubular sections 4 and 5 secured together by a suitable connection 6.

In Fig. 2, the connection is made by providing the upper section 4 with a reduced threaded neck 7 forming an outer annular stop shoulder 8 with the outer face thereof while the lower section 5 is provided with an internal threaded socket portion 9 to engage the threads of the neck 7 which terminates in an internal shoulder 10 for engaging the end face 11 of the neck when the shoulder 8 engages the upper end 12 of the socket to provide a tight joint and a substantially continuous wall structure.

If desired, the joint may be additionally secured by a cementitious material or gaskets between the shoulders 8 and 10.

The bottom end of the wall section 5 is provided with a closure member 13 including an externally threaded body portion 14 engaging internal threads 15 formed in the lower end of the section 5 and which is retained against rotation therein by fastening devices such as screws 16 extending through counter sunk openings 17 in the wall of the section and into threaded openings 18 in the threaded body portion 14. The lower end of the body portion terminates in a funnel shaped bottom 19 having a depending lug 20 provided with a transverse aperture 21 to which may be attached a hollow cylindrical anchor tubing for the purpose of placing or anchoring the filled container at a predetermined depth above the bottom of the well or by which a suitable weight may be secured to retain the container in axial alignment with the well casing.

45 The end of the upper section is internally threaded as at 22 to receive an externally threaded fill or funnel member 23 through which the nitro-glycerine is poured into the container. The fill member includes a body portion 24 of substantially the same diameter as that of the container and is provided with an externally threaded skirt portion 25 engaging in the threads 22 to secure the fill member to the container. The fill member is also locked in position by screws 26 extending through counter sunk openings 27 in the shell and into threaded sockets 28 formed in the skirt 25.

The upper end of the funnel member is provided with a conical recess 29 terminating in a channel 30 that is formed in a boss 31 depending from the body portion 24. The funnel member is provided with one or more air outlet ports 32 extending from the upper portion of the recess 29 through the body portion and communicating with the interior of the shell through the space 33 between the boss 31 and skirt 25, as clearly shown in Fig. 5.

The funnel member is also provided with a suitable ball 34 having inwardly directed ends 35 anchored in the body portion 24.

70 In carrying out the present invention, the wall sections, as well as the bottom closure and funnel members are formed of wrapped or molded "bakelite", a material composed of specially prepared phenolic resins having extremely high dielectric qualities particularly adapted for nitro-

glycerin containers. Such material is also a poor conductor of heat and is resistant to abrasion, as well as frictional heat when the container is being lowered into the well. The material is also extremely dense in texture and is insoluble in nitro-glycerin, or the well fluids with which it may come in contact.

The material is also relatively light in weight and owing to its strength, the containers may be constructed with relatively thin walls, fully capable of withstanding hydrostatic well pressures and weight of the nitro-glycerin contained therein, as well as the weight of other filled containers that may be suspended therefrom, as in customary practice in placing large explosive charges.

The material while being extremely tough and resistant to breakage is readily disrupted into very small fragments under the force of an explosion so that the parts thereof will not in any way damage the well or flow of the well fluid through the oil sand.

While as above stated, the cylinder walls may be formed of molded "bakelite", I prefer to construct the wall sections of a plurality of layers of thin fabric or preferably unsized absorbent one-hundred percent cellulose paper capable of absorbing a phenolic binder or varnish and compressed into tubular form. The binder or varnish is a product of chemical reaction of formaldehyde upon phenol or cresol and in order to assure neutrality or alkalinity in the finished product, the chemical reaction is carried on in the presence of an alkaline catalyst, otherwise the product may contain considerable amounts of unreacted phenol or cresol, or intermediate products of chemical reaction that might produce acidity.

It is found that a certain percentage of nitrogen may be present depending upon the character of the paper and the particular refinement of chemical binder or varnish employed. This nitrogen would indicate that nitrogenous materials are present, but by using a particular alkaline catalyst, such as sodium hydroxide, it is possible to provide a binder substantially free of nitrogen. Likewise, by using an unsized one-hundred percent cellulose paper, the pulp for which has been broken down by an alkaline process instead of an acid process, it is possible to provide a paper substantially free of nitrogen or nitrogenous materials.

In constructing the sections, the absorbent paper or fabric is run through a bath of the prepared binder and then passed through a drying chamber, after which it is wrapped under tension upon a heated mandrel, and/or molded in a press, under high pressure.

The funnel and bottom members are preferably molded from "bakelite" as follows: phenolic resins in powdered or sheet form manufactured by the reaction of formaldehyde upon phenol or cresol in the presence of a particular alkaline catalyst, such as sodium hydroxide, are used in hot hydraulic presses having hardened steel molds shaped to produce the desired contour of the members.

In connection with the molding step, it is found that a considerable quantity of volatiles are produced. They may be eliminated, however, to a considerable extent by opening the press during molding operations.

In order to further remove any possibility of an under-cured or under-finished product, high heat is maintained over an extended period much beyond that which would normally be considered necessary for the reaction of phenolic materials.

When the containers are formed by the wrap process, they are additionally heated after the mandrel has been removed so as to assure full cure on the inside as well as on the outside of the container walls.

The finished product when completed is an insoluble and infusible body which presents a neutral or alkaline surface to the explosive and has comparatively high tensile and compressible strength as well as extremely high di-electric properties. It is impervious to heat, water, oil and most chemicals. It is of uncommon strength and toughness and will not warp or deteriorate with age.

The tube as well as the funnel and bottom members are readily machined to form the threaded joints which secure the parts together.

In Fig. 5 is shown a modified form of container wherein both ends are closed by solid molded "bakelite" plugs 35 and 36 having threaded portions 37 to be received in the threaded ends 38 of the tubing and having apertured lugs 39 through which a bail is installed for securing the lowering cable as well as the weight as in the ordinary container illustrated in Figs. 1 and 2.

This type of container is known as a bomb and is particularly constructed to resist the hydrostatic pressure of the fluid column in the well and for containing explosive and a timed or automatic detonating, exploding or igniting device for setting off the bomb.

In Fig. 6 is shown a modified method of securing the bail wherein twisted wires 40 are imbedded into the molded material and have projecting eyes 41 by which a bail is installed for securing the lowering cable. In this form of the invention, the upper and lower sections are secured together by a threaded insert 42 formed of the same material as that of the sections.

In Fig. 7 the head of the funnel member is provided with horizontal openings 43 through which the ends 44 of a wire bail 45 are threaded to be attached to the body of the bail portion, as shown at 46. In this form of the invention, the insert 47 is simply a sleeve cemented to the inner face of the abutting sections.

In using a container constructed and assembled as described, the nitro-glycerin is poured into the funnel member so that it flows through the channel 30 to fill the container.

As the liquid nitro-glycerin enters the container air is expelled through the openings 32.

The required length of hollow cylindrical anchor tubing 48 is secured to the lug 20 by a nail or rivet 49 extending through the transverse rivet therein or a suitable weight, not shown, may be secured to the lug 20, as the case may require and the loaded shell is lowered into the well by a cable 50 and a detachable torpedo hook 51 attached to the bail 34.

The container is then rapidly lowered into the well, but friction thereof with the walls of the well will not generate static electricity, nor will friction cause heating of the nitro-glycerin even though the well be extremely crooked and the

container contacts with the well casing during the major portion of its descent.

If a large explosive charge is required, additional filled shells may be inserted between the first shell and the anchor tubing 48. A bomb such as shown in Fig. 5 may be connected between the hook and the upper container, as shown in Fig. 1.

When the shell or shells is or are in position, the nitro-glycerin may be detonated, exploded, 10 or ignited in the customary manner. The explosion occurring will completely shatter the container into small fragments which may be readily ejected or flowed out without causing damage to the well or injury to persons in the 15 vicinity thereof.

A container constructed as described is entirely free of acidity and does not subject the nitro-glycerin to decomposing effects that might produce premature explosions. 20

It is thus apparent that the shell may be safely set at any predetermined depth in deep or crooked wells without danger of premature explosions that might seriously damage or cause loss of the well. 25

It is also apparent that due to the solidity of the shattered shell fragments, they cannot cause injury to the sand or otherwise obstruct the flow capacity of the well.

What I claim and desire to secure by Letters Patent is:

1. A nitroglycerin container formed of dielectric material treated to eliminate acidity normally present in the material.

2. A nitroglycerin container including a shell 35 formed of fibrous material, and a binder produced by reaction of formaldehyde upon phenol in the presence of a sufficient amount of an alkali to insure against presence of acid in the shell at any time during effective life of the 40 shell.

3. A nitroglycerin container including a shell formed of a carrier, and a binder produced by reaction of formaldehyde upon phenol in the presence of a sufficient amount of an alkali to insure against subsequent reaction of residual acidity in the finished shell with nitroglycerin contained within the shell.

4. A nitroglycerin container including a shell formed of fibrous material, and a phenolic binder 50 containing a sufficient amount of an alkali to neutralize any acidity set up in the shell by reaction of components of the finished shell.

5. A nitroglycerin container including a shell composed of cellulosic material and a binder, 55 both substantially free of nitrogen and containing a sufficient amount of an alkali to insure against subsequent reaction of acid occurring in the material of which the shell is composed with nitroglycerin contained within the shell.

6. A nitroglycerin container having the characteristics set out in claim 2, but in which formaldehyde is reacted with cresol in manufacture of the binder element.

CAREY O. RISON. 65
